US0D1072939S

(12) **United States Design Patent** (10) **Patent No.:** **US D1,072,939 S**
(45) **Date of Patent:** **** Apr. 29, 2025**

(54) **CORNHOLE BOARD**

(71) Applicant: **Shenzhen Manyu Technology Co., Ltd.**, Shenzhen (CN)

(72) Inventor: **Yingfang Cai**, Shenzhen (CN)

(73) Assignee: **Shenzhen Manyu Technology Co., Ltd.**, Shenzhen (CN)

(**) Term: **15 Years**

(21) Appl. No.: **29/968,535**

(22) Filed: **Oct. 17, 2024**

(51) **LOC (15) Cl.** **21-01**

(52) **U.S. Cl.**

USPC **D21/322**

(58) **Field of Classification Search**

USPC D21/300, 302, 303, 322, 698
CPC A63B 63/00; A63B 63/08; A63B 67/06;
A63F 9/0204
